UNITED STATES PATENT OFFICE.

GEORGE W. SHAILER, OF PALMERSTON NORTH, NEW ZEALAND, ASSIGNOR
OF TWO-THIRDS TO JOHN HERBERT HANKINS, OF SAME PLACE.

APPARATUS FOR EAR-MARKING SHEEP.

SPECIFICATION forming part of Letters Patent No. 516,228, dated March 13, 1894.

Application filed April 22, 1893. Serial No. 471,511. (No model.)

To all whom it may concern:

Be it known that I, GEORGE WILLIAM SHAILER, a subject of the Queen of Great Britain, residing at Palmerston North, in the provincial district of Wellington, in the Colony of New Zealand, have invented certain new and useful Improvements in Apparatus for Ear-Marking Sheep and for other Similar Purposes, of which the following is a specification.

The objects of my invention are to provide a ready means of attaching labels or tickets to the ears of sheep and other animals, also to articles requiring to be labeled, whereby the said labels or tickets are very easily and securely attached, can be marked with a number or record which cannot be readily removed or altered; and in the case of animals the operation of clipping the ears or branding which often entails cruelty is obviated. I perform these objects by apparatus illustrated in the accompanying sheet of drawings in which—

Figure I is a perspective view of the whole of my apparatus when opened for use. Fig. II is a perspective view of the same when closed. Fig. III is a section taken through the line A B in Fig. I. Fig. IV is a perspective view of the ticket or label. Fig. V is a similar view showing the ticket or label fastened in position, and Fig. VI is a section taken through the line C, D, in Fig. I.

Similar letters refer to similar parts in all the figures.

(a) and (b) are the sides of a pair of pliers or tongs (hereinafter called "the pliers") having a pivot (b') on which they oscillate, and a spring (b²) to hold them in position for use (see Fig. I). The side (a) of the pliers terminates at its working end in a jaw or seat (a) which is fitted with grooves (a³) for a purpose to be hereinafter described, and above the jaw (a') is fitted a spring plate (a²) riveted or fastened on in such a manner that it has a slight tendency to spring upward and apart from the plate (a') at its outer edge. The side (b) of the pliers terminates in a jaw or plate (b³) shaped so as to nearly coincide in form to the label or ticket to be used, and

fitted with guides (b⁴) which are joined together by a bar (b⁵), which bar is suspended by a spring (d) fastened by a screw (d') at one end, and a clip (d²) at its other end, grasping a pin (d⁴) and steadied by a plate (d³). The guides (b⁴) and bars (b⁵) are fitted with a rib (b⁶)—see Fig. III—to prevent the label or ticket (f) being pushed too far in, and forms a guide for the same when in position for fixing.

(b²) is a spring to hold the pliers apart and (e) is a clip having a socket (e²) moving on a pin (e') so as to clip over the projection (e³) and within the recesses (e⁴) to hold the apparatus together when not in use.

(c) is a projection for steadying the hand.

(f) is the ticket or label, which can be made in any convenient form or size and can be marked, numbered or punctured in any distinctive manner. These labels are preferably made of thin sheet steel but can be made of any suitable metal, alloy or material. They are provided with projections (f') which are pointed at their ends (f²) and contracted at the bends, not only for ease in bending but to allow the punctures made in the ears to fit loosely round the narrow part and to hold more firmly when the ear has healed.

The mode of operating in labeling an animal is as follows:—The ticket or label (f) is placed under the plate or jaw (b³) and against the rib (b⁶) with the projections (f') pointing downward and steadied by the guides (b⁴). The ear of the animal is then placed between the two jaws which are then closed until the guides (b⁴) rest on the lower jaw (a') and the projections (f') enter the ear of the animal, then by the further descent of the jaw holding the label the projections (f') are pressed through the ear into the grooves (a³) and in so doing are curved inward and turned round under the ear to be labeled as shown by dotted lines in Figs. V and VI. By this operation the spring plate (a²) is depressed and rests on the top of the curve of projections (f')—see Fig. VI—but so soon as the label has been secured and the pliers are freed the spring plate (a²) rising frees the ear with its label which can then be easily drawn from between the jaws and the operation is com-

pleted, the label being fixed without compressing the ear too severely and the projections (f') curled round so as to prevent the ends from catching obstructions with which 5 they may come in contact.

I have herein described the method of marking the ears of animals but it will be evident that articles such as parcels, bales or fabrics may be labeled in a like manner with suitable labels and modification of the jaws of the apparatus. Also instead of curving the 10 points of the labels they may be simply returned under the object to make the label fast. Moreover my apparatus may be modified by a skillful workman without departing 15 from the principle of my invention.

Having now particularly described and ascertained the nature of my said invention and

in what manner the same is to be performed, I declare that what I claim is—

1. In combination, the pliers, the lower jaw having a groove at each side, a spring plate slightly over-lapping the grooves and an upper jaw having guides for the prongs of the label, substantially as described. 20

2. In combination, the pliers, the grooved lower jaw, the spring plate a^2 , the upper jaw and the spring supported guides b^4 , substantially as described. 25

In witness whereof I have hereunto set my hand, this 7th day of March, 1893, in the presence of two witnesses.

G. W. SHAILER.
